US00D890792S

(12) **United States Design Patent** (10) **Patent No.:** **US D890,792 S**
Valladares et al. (45) **Date of Patent:** **** Jul. 21, 2020**

(54) **DISPLAY SCREEN OR PORTION THEREOF
WITH A GRAPHICAL USER INTERFACE**

(71) Applicant: **JPMorgan Chase Bank, N.A.**, New York, NY (US)

(72) Inventors: **Amanda Valladares**, Brooklyn, NY (US); **Amanda Smith**, Brooklyn, NY (US); **Melora Zaner**, New York, NY (US); **Matthew Gromada**, New York, NY (US); **Jay E. Parsons**, Columbus, OH (US); **Jonathan Beck**, New York, NY (US); **Erika Scott**, Brooklyn, NY (US); **Claudio Esposito**, New York, NY (US); **Indeevara H. De Silva**, Lewis Center, OH (US); **Melissa Feldsher**, New York, NY (US); **Geoffrey L. Goetz**, Hilliard, OH (US); **Michael Thornton**, Westerville, OH (US); **Kimberly Chan**, New York, NY (US)

(73) Assignee: **JPMORGAN CHASE BANK, N.A.**, New York, NY (US)

(**) Term: **15 Years**

(21) Appl. No.: **29/670,456**

(22) Filed: **Nov. 15, 2018**

(57) **CLAIM**

The ornamental design for a display screen or portion thereof with a graphical user interface, as shown and described.

DESCRIPTION

The FIGURE depicts a front view of a display screen or portion thereof with a graphical user interface showing our design.

The broken line showing a display screen with graphical user interface is included for the purpose of showing portions of the article which form no part of the claim.

1 Claim, 1 Drawing Sheet
